UNITED STATES PATENT OFFICE.

FRANK B. HOWELL, OF BUFFALO, NEW YORK, ASSIGNOR TO AMERICAN RADIATOR COMPANY, OF NEW YORK, N. Y., A CORPORATION OF NEW JERSEY.

BOILER.

Application filed April 6, 1925. Serial No. 21,118.

My invention relates to improvements in heating apparatus and the same has for its object more particularly to provide a boiler for heating purposes in which the fuel will be consumed efficiently and smokelessly.

Further, said invention has for its object to provide a boiler having a large mass of highly heated material disposed in and about the combustion chamber whereby to maintain a temperature above the ignition point of combustible gases prior to and during the time the same are being supplied with pre-heated secondary air to insure the perfect and complete combustion of said gases.

Further, said invention has for its object to provide a boiler in which secondary air is supplied to the products of combustion at the rear of the fuel receptacle and, in which, prior to its combination with the products of combustion, the air is preheated by exposure to the heat radiated and conducted to the same from the incandescent fuel in said receptacle.

Further, said invention has for its object to provide a boiler in which the means for supplying secondary air serves as the rear wall of the fuel receptacle, and is exposed to the heat of the incandescent fuel upon the grate.

Further, said invention has for its object to provide a boiler in which the means for supplying secondary air, which means forms the rear wall of the fuel receptacle, is formed of a plurality of parts or sections whereby to permit of the ready removal of parts which may become damaged by exposure to heat, and to permit of the substitution of new parts therefor.

Further, said invention has for its object to provide a sectional wall of the type specified in which the parts thereof are independently mounted to permit the individual removal thereof, and in which the same are arranged edge to edge to provide a substantially continuous rear wall for the fuel receptacle.

Further, said invention has for its object to provide a boiler in which the secondary air is supplied to the products of combustion in a series of jets extending entirely across the boiler at the rear of the fuel receptacle.

Further, said invention has for its object to provide a boiler in which secondary air, in a highly heated condition, is supplied to the products of combustion as the same pass towards the flue and the mixture then di-

rected towards a facing of heat absorbing material whereby to maintain the temperature thereof sufficiently high to insure complete combustion.

Further, said invention has for its object to provide a boiler having means affording convenient access thereto to permit of the replacing of such parts of the superimposed rows, forming a facing of heat absorbing material, as may become burned out or otherwise damaged in the course of operation.

Other objects will in part be obvious and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawings forming part of this specification—

Figure 1 is a side elevation with parts broken away and with parts in section showing one form of boiler constructed according to and embodying my said invention;

Fig. 2 is a front elevation of bridgewall sections thereof, a center grate support being shown in section;

Fig. 3 is a partial sectional view thereof on the line 3—3 of Fig. 2, looking in the direction of the arrow;

Fig. 4 is a sectional view on the line 4—4 of Fig. 2 looking in the direction of the arrow;

Fig. 5 is a sectional view similar to that of Fig. 4, with the parts thereof disassembled;

Fig. 6 is a sectional plan view of the parts illustrated in Figs. 4 and 5;

Fig. 7 is a perspective view of a plate or member employed for forming the secondary air supplying means;

Fig. 8 is a side elevation of a portion of the boiler showing means for permitting access to the interior thereof;

Fig. 9 is a front elevation of portions of the baffle sections of the boiler, with parts in section, and showing a facing of heat absorbing material thereon and means for permitting access thereto;

Fig. 10 is a sectional view thereof on the line 10—10 of Fig. 9, looking in the direction of the arrow;

Fig. 11 is a front elevation of the rear sections with parts in section, and showing a facing of heat absorbing material thereon,

and means for permitting access thereto, and

Fig. 12 is a partial sectional view thereof on the line 12—12 of Fig. 11, looking in the direction of the arrow.

5 Referring to the drawings the boiler is shown as comprising separate halves 20 and 21 arranged laterally side by side, and each composed of a plurality of hollow sections including a front section 22, a back section 23, 10 and a plurality of intermediate sections 24.

The intermediate sections 24 and the bridge-wall sections 25 comprise outer lower vertical portions 26 forming the side walls of the boiler, and inwardly extending upper portions 27 forming the top of the boiler, corresponding sections of the half parts 20 and 21 being arranged adjacent to each other and enclosing the combustion chamber 28, fuel receptacle 29, flues 30 and ash pit 31. (Fig. 1.)

20 The portions 26 of the several sections 23, 24 and 25 of each part or half 20 or 21 of the boiler are provided with registering or aligned openings 32 in which are disposed the usual nipples (as shown at the upper portion 25 of Fig. 1) whereby the several sections are maintained in assembled relation and in communication with each other to provide free circulation of fluid through the boiler.

In like manner the upper portions 27 of 30 each set of sections are provided with aligned or registering openings 32 (Fig. 1) and secured by nipples 33.

35 A manifold 34 (Fig. 1) is secured at its opposite ends to the upper portions of the back sections 23, and has a single flow connection or outlet 35 intermediate its ends. The lower portions of said back sections 23 are similarly connected by a manifold 36 which has a return flow connection or member 37.

40 At a suitable point intermediate the front and back sections are provided registering intermediate sections 25 having inwardly extending hollow vertical members 38 forming bridgewalls communicating at the outer ends thereof with the vertical portions 26 of said intermediate sections 25, and having integral hollow risers 39 at the inner contiguous ends communicating with the upper portions 27 of the intermediate sections 25. The bridgewalls 38 together with the front sections 22 and side members 26 form the fuel receptacle 29 and ash pit 31.

45 Grate bars 40 (Fig. 1) which are arranged in sets upon opposite sides of the boiler are supported at their outer ends on the sections 26 which form the longitudinal or side walls of the boiler, and at their inner ends upon opposite sides of a common water backed central grate support 41 (Fig. 2) mounted between and upon the front sections 22 and bridgewalls 38. The grate bars 40 of each set or half of the boiler sections 20, 21 are movably mounted, and are provided with 50 downwardly extending arms 42 connected to

bars 43 whose forward ends extend through the front sections and are secured to levers 44 adapted to be engaged by a shaker bar whereby said grates may be actuated.

55 The boiler is enclosed by a jacket 45 of heat insulating material and is provided at the front with the usual fire doors 46, and ash pit doors 47 having openings 48 having regulating slides for controlling the admission of air.

75 Mounted upon the front upper portion of the vertical bridgewalls 38 is means 49 for supplying secondary air to the products of combustion in the combustion chamber 28 as the same enter the flues through openings or outlets 50 above the bridgewalls 38, the openings 50 being substantially coextensive in length with the width of the fuel receptacle.

80 Means 49 comprises an auxiliary vertical wall or member 51 constituting the rear wall of the fuel receptacle and spaced from the bridgewalls 38 to provide between the same a vertical opening or openings 52. Said member 51 terminates at its lower edge 53 slightly below and behind the grate bars 40, whereby each opening 52 is in communication with the ash pit at one end 54 and with the combustion chamber 28 at its opposite end 55.

85 The member or members 51 (the member being in parts arranged upon opposite sides 90 of the central grate support 41 and risers 39) are preferably sectional, comprising sectional members or plates 56 arranged to provide a continuous wall, and, as illustrated, edge to edge.

95 The plates or members 56 are independently and detachably mounted upon the bridgewalls 38 to permit the individual removal thereof as the same become damaged, and also to permit independent expansions there- 100 of to prevent warping.

105 For this purpose the fronts of the water backed bridgewalls 38 are provided with vertical water backed supporting members or brackets 57 projecting outwardly therefrom and arranged in spaced relation along the said bridgewalls 38. Each supporting member 57 comprises laterally projecting plate retaining members or flanges 58 at the forward portions of the same arranged in parallelism with the bridgewalls. The retaining members or flanges 58 have notches 59 therein intermediate their upper and lower ends, and supporting devices or ledges 59^a behind the same below said notches 59 to support plates 56.

110 Each plate 56 (Figs. 4 to 7) is provided with a plurality of vertically arranged ribs 60 upon its inner surface, the outer of the ribs having upper and lower sets of spaced lugs 61 constituting means for mounting the plates upon the lugs 59^a of the brackets 57 behind the members 58. The lugs 61 are so located on each plate as to permit the plates 56 to be inserted between adjacent members 130

57 with the ribs 60 thereof occupying the spaces between flanges 58 (see Fig. 3), the upper set of lugs 61 being passed over the top of the flanges 58 and the lower set of lugs 5 61 through the notches 59 thereof. The plates 56 are then lowered or permitted to drop, the lower lugs 61 engaging the ledges 59^a, thereby supporting the plates in position with the lugs 61 thereon positioned behind the retaining 10 members 58.

Means is also provided for deflecting the secondary air rearwardly as the same enters the combustion chamber 28. This means is formed by constructing the upper end of each 15 plate with an upwardly and rearwardly directed angular portion 62 whereby the vertical opening 52 at the upper end 55 thereof is constricted, said angular portion 62 at the inner side having rib portions 60^a constituting upper continuations of the ribs 60.

The ribs 60, 60^a not only serve to strengthen the plates 56 but also provide means or channels for increasing the metal surface in contact with the secondary air to more efficiently 20 heat the same.

The opening 52 is divided into vertical passages or channels 63 by said brackets 57 to form means for dividing the secondary air to supply the same in jets to the products of 30 combustion. As shown more clearly in Fig. 3 the rib portions 60^a also further divide the upper end of the opening 52 to provide a plurality of constricted passages or outlets 64 for supplying the secondary air in jets to the 35 products of combustion. The passages 63, 64 formed by the brackets 57 and ribs 60^a are arranged substantially coextensive with the width of the fuel receptacle insuring the supply of a maximum quantity of secondary air 40 in jets to the products of combustion, while permitting the removal and replacement of the plates 56, should the same become damaged.

The products of combustion combined with 45 the rearwardly deflected secondary air impinge, in passing through the openings 50, upon hollow baffles 65 (Figs. 1, 9 and 10) communicating at the outer ends thereof with the vertical portions 26 of a pair of contiguous 50 intermediate sections 24, and communicating at their inner contiguous ends with the portions 27 of the same sections through integral hollow risers 66.

The fronts of baffles 65 are provided with 55 facings 67 of heat absorbing and retaining material against which the gases or products of combustion impinge and which insure complete combustion thereof by the maintenance of a high temperature thereby in the vicinity 60 of the combustion chamber 28 where the secondary air combines with the products of combustion.

In like manner the bottom or floor of the flue 30 is provided with a facing 68 of heat 65 absorbing and retaining material which the

products of combustion pass as the same sweep downwardly between the bridgewalls 38 and baffles 65. The products of combustion are then directed upwardly between the baffles 65 and the water backed rear sections 70 23 which have facings 69 of heat absorbing material thereon. The provision of the several heat retaining surfaces 67, 68 and 69 within the flues 30 maintains the interior thereof at a sufficiently high temperature to 75 insure complete combustion of the gases before the same enter the galleries 70 and pass out at the rear thereof through the outlet 71 to the chimney.

The facings 67 on the baffles 65 preferably 80 comprise a row of blocks or brick 67^a mounted in horizontal guideways or supports 72 formed in the baffles. The guideways 72 include spaced horizontal ledges or retaining members 73 between which and in which the blocks 67^a are supported and retained, said ledges converging towards each other at the fronts. The ledges 73 of the baffles 65, are aligned or register at their inner ends 74, forming a substantially continuous guideway, and 90 are open at their outer ends 75 to permit the removal therefrom or the insertion therein of blocks through openings 76 in the side portions of the baffle sections 24 and jacket 45. As shown in Figs. 9 and 10, the openings 76 95 at opposite sides of the boilers are surrounded by frames 77 having flanges 78 inserted along the edges of the openings 76, and secured against the jacket 45 by means of bolts 79 extending through the jacket 45 and secured 100 in openings or holes 80 in the baffle sections 24. The openings 80 are backed by a cup shape partition 81 to prevent leakage. The opening through each frame 77 is closed by a removable cover 82 secured to the frame 105 by rotatable locking bolts 83. The bolts 83 have fingers 84 at their inner ends adapted to engage behind ledges 85 on the frames 77, and handles 86 at their outer ends whereby the bolts 83 may be rotated to disengage the ledges 85 and to remove the covers 82. The guideways 72 are also provided with horizontal ribs 87 to space the blocks 67^a from the baffles 65 to reduce the rate of conduction of heat from the blocks 67^a to the baffles 65 which, 115 being water backed, would tend otherwise to cool said blocks.

The facings 69 (Figs. 1, 8, 11 and 12) upon the rear sections 23 comprise a plurality of horizontal rows 88 of blocks or brick 69^a 120 of heat absorbing material. The rows 88 are independently mounted in superimposed horizontal guideways or supports 89 formed on the fronts of the rear sections 23. The supports 89 comprise horizontal top and bottom brick or block retaining flanges or ledges 90 and intermediate ledges or flanges 91 parallel therewith, whereby the rows 88 are independently supported between adjacent flanges in 125 spaced relation to each other. 130

The inner ends of the several flanges 90, 91 on the sections 23 are alined or register, forming substantially continuous guideways from side to side of the boiler and the outer ends 92 are open to permit the removal and insertion of the blocks 69^a through openings 93 in opposite sides of the boiler, which openings are common to the plurality of rows 88 at opposite ends thereof.

10 The openings 93 are surrounded by frames 77^a (similar to the frames 77 previously described) common to the plurality of rows 88 at opposite ends. Each frame 77^a is secured against the jacket 45 and a rear section 23 by bolts 79^a secured to the section 23. The openings in said frames 77^a are normally closed by the covers 82^a common to the several rows at opposite ends thereof, the covers being secured in place by locking bolts 83^a constructed and arranged as previously described in connection with the bolts 83 shown in Figs. 9 and 10. The guideways 89 are likewise provided with ribs 87^a to space the blocks 69^a from the water backed rear section 23 to prevent the too rapid conduction of heat absorbed by said blocks to the cooler section 23.

In operation the air is supplied from the ash pit 31 upwardly through the grates 40 to the fuel thereon causing the same to burn. 30 The partially consumed products of combustion or gases thus formed pass rearwardly (as indicated by the arrows Fig. 1) towards the openings 50 where secondary air is supplied thereto to combine therewith to insure complete combustion. The secondary air is also supplied from the ash pit through the openings 52 at the rear of the fuel receptacle 29. In passing through the opening 52 the secondary air, which is directly exposed to 40 the heat of incandescent fuel in the receptacle 29, becomes preheated, said air being in contact with the relatively large metal surfaces consisting of the plates 56 with the ribs 60 thereon which directly receive said heat by conduction and radiation from the incandescent fuel. The preheated secondary air passing through the passages formed by the ribs 60^a and brackets 57 escapes in jets from the 45 openings 64 and combines in the chamber 28 with the partially consumed products of combustion, said jets permitting maximum contact and combination thereof with the products of combustion. The products of combustion then pass rearwardly and impinge on 50 the facings 67 of heat absorbing material, the latter absorbing and retaining heat therein to maintain the adjacent portions of the boiler at a high temperature to insure complete combustion. As the products of combustion pass 60 into the flues 30 the facings 68 and 69 are highly heated, the heat being retained thereby to maintain the interior of the flues at a maximum temperature, thereby causing complete combustion and maintaining the products of combustion passing the same at a

maximum temperature so that the water circulating in the portions 27 of the boilers about the galleries 70 will be efficiently heated as such highly heated products of combustion pass therethrough. The quantity of secondary air supplied to the products of combustion is automatically controlled by the rate of combustion.

Should any of the plates 56 become cracked or broken the same may be easily removed and 75 a new one inserted in place as above described.

In case any of the blocks 67^a, 69^a become broken or cracked and fall into flue portion 30, the closure or closures 82 or 82^a are unlocked and removed, the blocks remaining in 80 place are moved along by a suitable instrument or tool inserted through the opening, to fill up the spaces left by the blocks which have dropped out, and new blocks are inserted through the opening to complete the row. 85 The closure or closures are then replaced to maintain the side walls air tight or to prevent the escape of the products of combustion therethrough. By independently mounting the rows 88 any block in one row may be 90 readily removed and replaced without disturbing any of the other rows.

The secondary air supplying means 49 embodying my said invention provides a construction which is simple, and readily and 95 conveniently arranged in the boiler. The same is positioned to be exposed to the heat of the incandescent fuel in the fuel receptacle, thereby insuring a maximum preheating of the secondary air for combination with the 100 products of combustion.

The sectional wall and the independent mounting of the constituent parts thereof permits unequal expansion of said parts due to heat without distortion or warping thereof 105 and the individual replacement of said parts.

Further, a sectional rear wall for the fuel receptacle is provided which is substantially continuous and which with the bridge wall forms an opening therebetween for feeding 110 air to the products of combustion at points substantially coextensive with the width of the fuel receptacle.

Further, the preheated air combines with the products of combustion in the vicinity of facings of heat absorbing and retaining material which maintain the flues at a sufficiently high temperature to cause complete combustion and to insure the delivery of the gases at such high temperature to heat the 115 water circulating in the boiler.

By my invention a boiler is provided which is substantially smokeless and which will burn soft coal with the greatest economy.

Having thus described my said invention, what I claim and desire to secure by Letters Patent is—

1. A boiler comprising a water backed transverse vertical wall, a sectional member arranged in parallelism with said wall, and 120

coextensive in area with the portion thereof extending above the grate, and means including water backed members on said wall for detachably engaging and supporting the elements of said sectional member separately; 5 said sectional member being spaced with respect to said wall and having its lower edge wholly free thereof to provide means for the vertical passage of secondary air therebetween to the products of combustion, substantially as specified.

2. A boiler comprising a fuel receptacle, a transverse vertical wall at the rear of said fuel receptacle, and a plurality of plates severally detachably secured to the front of said wall and constituting the unbroken rear wall of said fuel receptacle; said first named wall and said plates being spaced relative to each other to provide means for the passage of secondary air therebetween to the products of combustion, and said plates having their upper ends inclined rearwardly to form jointly a deflector, substantially as specified.

3. A boiler comprising a transverse vertical wall, a member composed of a plurality of plates, means on said wall for severally securing said plates on said wall and in spaced relation thereto with their lower edges wholly free thereof and constituting therewith means for the passage of secondary air to the products of combustion, and means for dividing said air into a plurality of jets, substantially as specified.

4. A boiler comprising a transverse vertical wall, a series of separate plates detachably secured to said wall in spaced relation thereto and constituting therewith means for the passage of secondary air therebetween, and means dividing the space between said plates 40 and said wall into a plurality of vertical passages for feeding said air in jets to the products of combustion as the same pass over said wall, and means along the upper edge of said series of plates for deflecting the secondary air rearwardly over said transverse vertical wall, substantially as specified.

5. A boiler comprising a transverse vertical wall, a member arranged at one side of said wall, and means for mounting said member 50 in spaced relation to said wall; said means forming a plurality of vertical passages between said wall and member for the passage of secondary air to the products of combustion, substantially as specified.

55 6. A boiler comprising a transverse vertical wall, a sectional member arranged at one side of said wall, and means for detachably mounting said member on said wall in spaced relation thereto; said means forming a plurality of vertical passages between said wall and said member for the passage of secondary air therethrough to the products of combustion, substantially as specified.

65 7. A boiler comprising a transverse vertical wall and a parallel member arranged at

one side thereof in spaced relation thereto; said wall and member having its top curved rearwardly, and terminating in a plane above said wall to form a constricted opening therebetween for the passage of secondary air 70 therethrough to the products of combustion, and means arranged upon the back of said member dividing the space to the rear of said member into a plurality of air passages, substantially as specified.

8. A boiler comprising a transverse vertical wall, a plurality of plates having angularly arranged ends, vertical ribs on said plates, and means for detachably securing said plates separately to said wall in spaced relation 80 thereto; said angularly arranged ends and the upper edges of said wall forming a constricted opening therebetween substantially coextensive with the width of said wall, and said ribs and said securing means forming vertical passages between said plates and said wall for the passage of said air in jets through said opening to the products of combustion, substantially as specified.

9. A boiler comprising a fuel receptacle, a wall at the rear thereof, a plurality of plates detachably mounted upon the front of said wall and forming the rear wall of said fuel receptacle; said plates and first named wall being spaced to provide a vertical opening 90 therebetween substantially coextensive with said fuel receptacle for the passage of secondary air therethrough to the products of combustion, and means intermediate said wall and said plates for dividing said opening into 100 passages for separating said air into jets, substantially as specified.

10. A boiler comprising a fuel receptacle, a water backed wall at the rear thereof, a plurality of plates detachably mounted upon 105 the front of said wall and forming the rear wall of said fuel receptacle; said plates and first named wall being spaced to provide a vertical opening therebetween for the passage of secondary air therethrough to the 110 products of combustion, the upper portions of said plates being directed rearwardly to constrict said opening, and ribs thereon to form a plurality of passages to separate said secondary air into jets, substantially as specified.

11. A boiler comprising a fuel receptacle, an outlet for the products of combustion at the rear thereof, a transverse vertical wall at the rear of said fuel receptacle, and a series 120 of separate members mounted in front of said wall in spaced relation thereto and forming the rear of said fuel receptacle; each of said separate members having its upper end directed rearwardly to said outlet whereby to deflect the secondary air passing upwardly between said member and said wall, substantially as specified.

12. A boiler comprising a transverse water-backed vertical wall, a plurality of spaced 130

- supporting members arranged along said wall, and a plurality of members independently mounted on said supporting members and parallel with said wall and forming therewith 5 a continuous imperforate wall having a rearwardly inclined upper edge forming a deflector; said imperforate wall constituting the entire rear wall of the fuel receptacle, substantially as specified.
10. 13. A boiler comprising a fuel receptacle, a transverse vertical water-backed bridge wall at the rear thereof, an outlet at the rear of said receptacle above said bridge wall, a sectional wall member located in front of said 15 bridge wall and forming the rear wall of said fuel receptacle; said bridge wall and said sectional wall member being spaced relative to each other to provide therebetween means for the passage of secondary air upwardly there- 20 through to combine with the products of combustion entering said outlet, means at the top of said sectional wall member for directing said secondary air rearwardly, and a water-backed baffle having a facing of heat absorbing 25 material associated with said bridge-wall and spaced rearwardly thereof in the path of said products of combustion, substantially as specified.
14. A boiler comprising a fuel receptacle, 30 a water backed wall at the rear of said fuel receptacle, an outlet at the rear of said receptacle above said wall, a water backed baffle spaced rearwardly of said outlet, a facing of heat absorbing material on the front thereof, 35 a plurality of plates detachably mounted upon the front of said wall and forming the rear wall of said fuel receptacle; said plates and wall being spaced to provide means for the passage of secondary air upwardly there- 40 between to the products of combustion entering said outlet; said means being substantially coextensive with said fuel receptacle, means for dividing the space between said plates and said walls into a plurality of vertical 45 passages to feed said air in jets, and means for directing said jets towards said facing, substantially as specified.
15. A boiler comprising a water-backed bridgewall, an outlet thereabove, a water backed baffle spaced rearwardly of said outlet, a water backed rear wall, facings of heat absorbing material upon the fronts of said baffle and of said rear wall, and a plurality of plates detachably mounted upon the front of 55 said bridgewall and constituting the rear wall of the fuel receptacle; said plates and bridge- 60 wall being spaced to provide means for the passage of secondary air upwardly therebetween to the products of combustion entering said outlet, substantially as specified.
16. A boiler comprising a transverse
- bridge-wall, a member associated with one side of said wall and comprising a plurality of similar elements, each having a rearwardly inclined upper edge and jointly forming 65 a deflector coextensive in length with said member, means for severally supporting said elements in end to end engagement upon said bridge-wall and in spaced relation thereto; the forward sides of said elements forming 70 an imperforate wall serving as the rear wall of the fuel receptacle, and vertical ribs arranged upon each of said elements serving to divide the space between the rear sides thereof and the front of said bridge-wall into a 75 plurality of vertical passages for conducting secondary air to mingle with the products of combustion as the same pass over the top of said bridge-wall, substantially as specified.
17. A boiler comprising a fuel receptacle, a 80 water-backed bridge-wall at the rear thereof, vertical water-backed brackets on the front of said bridge-wall having recesses in the edges thereof, and stops on said brackets below said recesses, a plurality of plates arranged in end to end engagement and in 85 spaced relation to said bridge-wall and forming an imperforate wall in front thereof; said plates each having a rearwardly inclined upper edge and jointly forming a longitudinal deflector coextensive in length with said bridge wall and each having lugs adapted to be received by the recesses in the brackets of said bridge-wall and to be supported upon the stops below the same whereby to hold said 90 plates in position upon said bridge-wall, substantially as specified.
18. A boiler comprising a fuel receptacle, a water-backed bridge-wall at the rear thereof, vertical water-backed supporting brackets extending therefrom, lateral flanges along the opposite longitudinal edges of said supporting brackets, said flanges having recesses in their edges, stops upon the rear sides of said flanges below the recesses therein, a plurality 95 of plates arranged in end to end engagement and in spaced relation to said bridge-wall and forming at their front sides an imperforate wall constituting the rear wall of said fuel receptacle; said plates each having a plurality of longitudinal ribs extending from the rear surface, and laterally extending lugs on certain of said ribs adapted to be received by the recesses in said flanges and to be engaged by said stops whereby to hold said 105 plates severally in position upon said bridge-wall, substantially as specified.
- Signed at the city of Buffalo, Erie County, State of New York, this 15th day of May, one thousand nine hundred and twenty-four.

FRANK B. HOWELL.
